UNITED STATES PATENT OFFICE.

RICHARD A. TERRY, OF ROANOKE, VIRGINIA.

OIL-BURNER.

1,110,516.

Specification of Letters Patent. Patented Sept. 15, 1914.

Application filed June 23, 1914. Serial No. 346,627.

To all whom it may concern:

Be it known that I, RICHARD A. TERRY, a citizen of the United States, residing at Roanoke, in the county of Roanoke and State of Virginia, have invented a new and useful Oil-Burner, of which the following is a specification.

The present invention appertains to oil or hydrocarbon burners, and aims to provide a novel and improved burner adapted to be disposed within or projected into the combustion chamber of a boiler furnace, heating furnace, or the like.

The invention contemplates the provision of an oil burner of unique construction, and embodying a novel assemblage of component parts, whereby the utility of the device will be enhanced.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein—

Figure 1 is a longitudinal section of the improved burner, parts being shown in full. Fig. 2 is an end view of the burner looking toward the outlet or nozzle end, and a portion being broken away. Fig. 3 is a sectional detail taken on the line 3—3 of Fig. 2. Fig. 4 is a sectional detail of the outlet or nozzle end of the burner, illustrating a modified form of spreader.

In carrying out the present invention, there is provided a cylindrical or tubular casing 1, the bore or passage 2 of which has its rear end contracted slightly, and threaded as at 3. The bore 2 is contracted in diameter adjacent its forward or outlet end, as at 4, and is tapered, as at 5, next inside the contracted or restricted portion 4. The outlet end of the bore 2 is counter-bored or countersunk, as at 6, to provide a rounded or hemi-spherical socket or recess at the nozzle or outlet end of the casing 1. The said casing is provided with a lateral opening or port 7 adjacent the basal or butt end of the casing 1 or the threaded opening 3 thereof. A supply pipe 8 for steam or

other pressure fluid is threaded into the opening or port 7, to supply steam or other atomizing fluid into the bore 2 of the casing, it being understood that the passage of steam or atomizing fluid through the pipe 8 may be controlled by any suitable valve (not shown).

A fuel or oil nozzle 9 projects forwardly within the casing 1, and is of smaller diameter than the said casing, the nozzle 9 being provided at its butt or basal end, with the slightly enlarged and threaded portion 10 which is threaded into the opening 3 of the casing 1 to maintain the nozzle in axial or concentric position within the casing. The rear or basal end of the nozzle 9 is provided with a head 11 which seats against the basal or rear end of the casing 1, and the bore or passage 12 of the nozzle 9 extends through the head 11. The forward or free end of the nozzle 9 terminates short of the contracted portion 4 of the bore 2, and is flared, as at 13, to provide a conical or tapered valve seat 14 within the forward end or tip of the nozzle 9. The head 11 or butt end portion of the nozzle 9 is provided with a lateral opening or port 15 leading to the bore 12, and into which is threaded the discharge end of the supply pipe 16 for the oil or other liquid fuel which is to be consumed.

A nipple 17 is threaded into the rear end of the bore 12, and a valve stem or spindle 18 which projects axially or centrally through the nozzle 9 and casing 1 is threaded through the nipple 17. A gland 19 is threaded upon the outer or rear end of the nipple 17, to compress the packing 20 tightly around the stem or spindle 18 to prevent leakage. The outer or rear end of the stem or spindle 18 is equipped with a suitable hand wheel 21 for convenience in rotating the stem or spindle to adjust the same longitudinally or axially.

A conical valve and spreader 22 is mounted or secured upon the stem or spindle 18 in any suitable manner adjacent the free end or tip of the nozzle 9, to coöperate with the seat 14, there being a mixing chamber 23 in advance of the valve and spreader 22 or between the free end of the nozzle 9 and the contracted portion 4 of the bore 2.

A collar or tubular member 24 is mounted upon the stem or spindle 18 within the contracted portion 4 of the bore 2 and serves to further restrict the passage or opening

through the contracted portion 4. Thus, the collar or tubular member 24, provides a restricted annular outlet for the mixing chamber 23 leading to the socket or recess 6. Pins 25 are engaged through the collar 24 and stem 18, and project from the collar 24 to provide fingers or lugs slidably engaging the walls of the contracted portion 4 to guide the forward end portion of the stem 18 for axial or longitudinal movement.

As illustrated in Figs. 1, 2 and 3, a peculiar form of spreading means is mounted within the socket or recess 6 for providing an arcuate upwardly-directed flame. This spreading means embodies a stationary removable face and closure member 26, which is of approximate lune-shaped contour, and which has its rounded side or base fitted snugly within the lower portion of the socket or recess 6 and equipped with a pair of depending lugs or pins 27 engaged through a pair of apertures or openings 28 formed in the lower or bottom portion of the nozzle end of the casing 1. Thus, the member 26 is removably held in place within the lower portion of the nozzle of the casing 1. The member 26 has one flat side or face arranged flush with the forward end of the casing 1; and its other flat side or face is disposed parallel with but slightly below the axis of the casing. The forward end of the stem or spindle 18 passes over the member 26, and the ends of the said member 26 are provided with upturned guide ears or lugs 29 resting against the side portions of the nozzle or forward end of the casing 1.

A spreader 30, which is of approximate lune-shape, is disposed within the upper portion of the socket or recess 6 above the member 26. One flat side of the spreader 30 is seated upon the upper flat side of the member 26, while the other flat side of the spreader 30 is normally disposed flush with the forward end of the casing 1. The curved side of the spreader 30 has a slightly shorter radius of curvature than the socket or recess 6, whereby the curved side of the spreader will be normally spaced from the upper and side portions of the socket 6 to provide an arcuate outlet slot for the nozzle end of the burner. The spreader 30 is slidably mounted upon the member 26 between the ears 29, and is mounted upon the forward end of the stem 18 to seat against the collar or tubular member 24. A nut or retaining element 31 is threaded or otherwise engaged upon the forward extremity of the stem 18 to retain the spreader 30 in place, it being observed that the stem 18 is rotatably mounted within the spreader. The spreader 30 and seat element or member 26 are jointly somewhat in the form of a hemisphere, the member 26 closing the lower portion of the outlet through the socket 6.

65 A second spreading means is illustrated in

Fig. 4 which may be interchangeably employed with the aforesaid spreading means 26-30. Thus, when the spreader 30 is removed and the seat element 26 withdrawn from the socket 6, a hemi-spherical spreader 32, as illustrated in Fig. 4, may be inserted or engaged upon the forward end portion of the stem 18, to be retained in seated position against the collar 24 by the retaining nut 31. The spreader 32 provides a circular or annular outlet slot to provide a circular or annular flame.

In practice, the burner may be applied to a boiler, furnace, or other structure, for purpose of heating the same. Supposing steam, compressed air, or other pressure fluid to be supplied through the pipe 8 to the casing 1, and supposing oil or other liquid fuel to be supplied through the pipe 16 into the nozzle 9, when the stem 18 is threaded or adjusted forwardly, the valve or spreader 22 will be forced away from the seat 14 and the spreader 30 or 32, which ever is employed, will be moved forwardly away from the opening or contracted portion 4 of the bore 2. The steam or atomizing fluid in passing the flared end 13 of the nozzle 9 and being directed away from the seat 14 by the said flared end 13, will tend to create a vacuum around the annular base or slot between the valve 22 and the seat 14 to thereby draw the oil into the mixing chamber 23 and to thoroughly atomize the oil. Within the chamber 23, the atomizing fluid and oil are thoroughly mixed under the agitating action of the atomizing or pressure fluid and the mixture is then discharged through the nozzle and around the spreader 30 or 32. When the stem 18 is threaded or adjusted rearwardly, the valve or spreader 22 may be brought tightly against the seat 14, and the spreader 30 or 32 drawn inwardly to close the outlet opening 4, so that the outlet or discharge for both the pressure fluid and oil will be stopped or checked. Should the burner become plugged up or stopped by the accumulation of sediment or foreign matter, the sediment or foreign matter may be ejected by threading the stem 18 forwardly to a considerable extent, whereby the pressure fluid will forcibly discharge the accumulated matter.

The pins 25 carried by the stem 18 and engaging the walls of the opening or contracted portion 4 of the bore 2 will hold the forward end portion of the stem 18 in proper position, and thereby properly hold the valve and spreader 22 in co-operative relation with the seat 14 of the nozzle 9, and to hold the spreader 30 or 32 in proper operative position.

When the spreader 30 is employed in connection with the seat element 26, the spreader 30 will be adjusted longitudinally upon the seat element 26 when the stem 18 is

is adjusted, to thereby provide an arcuate upwardly-directed flame when desired. When the spreader 32 is employed, there will be provided a circular flame, which may be desired at times.

From the foregoing, taken in connection with the drawing, the advantages and capabilities of the present invention will be obvious to those skilled in the art, it being noted that the present burner may be adapted to burn various oils or liquid fuels.

When both of the spreaders 30 and 32 are removed, the flame will be directed directly forward in the form of a needle flame, of considerable length, when so desired, the length of the flame being governed by the pressure of the atomizing or pressure fluid.

Having thus described the invention, what is claimed as new is:

1. A hydrocarbon burner including a casing having a pressure fluid inlet adjacent one end, a contracted outlet opening adjacent its other end and a socket next outside the contracted outlet opening, a nozzle projecting into the casing into the first mentioned end, an adjustable stem passing through the nozzle and casing, a valve and spreader carried by the stem and coöperating with the discharge end of the nozzle, the stem and contracted outlet opening having interengaging portions for guiding the stem for longitudinal movement, and a spreader carried by the stem within the said socket.

2. A hydrocarbon burner including a casing having a pressure fluid inlet adjacent one end, a contracted outlet opening adjacent its other end and a socket next outside the contracted outlet opening, a nozzle projecting into the casing from the first mentioned end, an adjustable stem passing through the nozzle and casing, a valve and spreader carried by the stem and coöperat-

ing with the discharge end of the nozzle, a collar mounted on the stem within the contracted outlet opening, pins engaging through the collar and stem, and engaging the walls of the said contracted outlet opening to guide the stem for longitudinal movement, a spreader engageable upon the stem and seatable against the said collar within the said socket, and retaining means engageable with the stem for holding the last mentioned spreader seated against the collar.

3. In a burner, a casing having an outlet opening adjacent one end and socket next outside the said opening, a stem extending through the said opening, a seat element disposed within one portion of the said socket and closing the same, and a spreader mounted upon the stem and fitting slidably against the said seat element.

4. A burner including a casing having an outlet opening adjacent one end and a socket next outside the said opening, a stem extending through the said opening, a seat element fitting within one portion of the socket, the seat element and casing having interengageable portions for removably holding the seat element in place, a spreader slidably engaging the seat element within the said socket, the stem being journaled through the spreader and having a collar against which the spreader is seated, and retaining means engaged upon the stem for holding the spreader in place.

In testimony that I claim the foregoing as my own, I have hereto affixed my signature in the presence of two witnesses.

RICHARD A. TERRY.
